Primary Examiner — Holly E Thurman(74) *Attorney, Agent, or Firm* — Crowell & Moring LLP**CLAIM**

The ornamental design for a stand and pivot unit, as shown and described.

DESCRIPTION

This application contains subject matter related to the following co-pending U.S. design patent application:
application Ser. No. 29/542,684, filed Oct. 16, 2015 and entitled "MICROSCOPE."

FIG. 1 is a front view of a stand and pivot unit according to the design;

FIG. 2 is a left side view thereof;

FIG. 3 is a right side view thereof;

FIG. 4 is a rear view thereof;

FIG. 5 is a front, left perspective view thereof;

FIG. 6 is a top view thereof; and,

FIG. 7 is a bottom view thereof.

The broken lines are for illustrative purposes only and form no part of the claimed design.
